GAS-AIR MIXER

Joseph F. Lovett, Northfield, N. J., assignor to
Archie R. Ammons, Millville, N. J.

Application March 24, 1955, Serial No. 496,530

1 Claim. (Cl. 158—118)

This invention relates to improvements in gas mixers and more particularly to an improved device for mixing combustible gaseous materials, such as natural gas or the like, with air.

In order to insure proper burning of natural gas and other high B. t. u. gases, it is essential that the gas be intimately intermixed with air before it is fired. The known mixers in use today capable of obtaining a proper combustible mixture of natural gas and air, such as pre-mixer devices and the like, are often prohibitive in cost whereas those of lesser cost, such as venturi-type inspirator mixers and the like, do not mix the gas and air sufficient to obtain proper burning. Since natural gas is more and more supplanting the use of manufactured gas, the need for an inexpensive gas-air mixer which will intimately mix the two gaseous substances sufficient to obtain proper burning is especially acute.

Accordingly, it is an object of the present invention to provide an inexpensive gas-air mixer which will function to intimately mix the gas and air so as to obtain proper burning thereof.

Another object of the present invention is the provision of an improved gas-air mixing device capable of mixing gas and air as intimately as does a pre-mixer, but yet is as economical to manufacture as the less effective venturi-type inspirator mixers.

A still further object of the present invention is the provision of a novel device for mixing two gaseous substances of materials which employs the principle of the fan to create a negative pressure to cause inspiration of one of the gaseous substances and turbulence to cause intimate intermixing of the two.

A still further object of the present invention is the provision of a novel gas-air mixer which is simple in construction, efficient in operation, and economical to manufacture and maintain.

These and other objects of the present invention will become more apparent during the course of the following detailed description and appended claim.

The invention may best be understood with reference to the accompanying drawings wherein an illustrative embodiment is shown.

In the drawings:

Figure 1 is a vertical sectional view of a gas-air mixing device embodying the principles of the present invention;

Figure 2 is a cross-sectional view taken along the line 2—2 of Figure 1;

Figure 3 is a cross-sectional view taken along the line 3—3 of Figure 1;

Figure 4 is a side elevational view of the first fan providing part of the device; and

Figure 5 is a side elevational view of the second fan providing part of the device.

Referring now more particularly to the drawings, there is shown in Figure 1 a gas-air mixing device, generally designated 10, embodying the principles of the present invention. The device comprises a main hollow body or

2

pipe 12 having a suitable fitting 14 threadedly engaged within the forward end thereof for connection to a suitable burner, superheater or the like (not shown).

Extending longitudinally within the pipe 12 through the opposite end thereof is a tube 16 for supplying air under any pressure to the interior of the pipe. The tube 16 may be secured to the pipe 12 in any desired manner, however, as shown, a short tubular fitting 18 is preferably employed which has its forward end threadedly engaged within the rearward edge of the pipe and its rearward end internally threaded for the reception of the tube 16. The tube 16 is provided with an externally threaded section 20 on its rearward portion for cooperatively engaging within the internally threaded rearward end of fitting 18. A suitable source of air under any desired pressure is supplied to the tube 16 by a suitably connected conduit 22 preferably having a control valve 24 therein.

The forward end of the tube 16 disposed within the pipe 12 is provided with a plurality of fan blades 26 for a purpose hereinafter to be more fully described. These blades are preferably struck from the metal of the tube by longitudinally cutting the same and then bending one longitudinal edge inwardly. As shown, three such blades are provided which impart a counterclockwise rotation to the air issuing from the tube, as viewed in Figure 2.

The fitting 18 may include a T-connection 28 through which a suitable source of gas is supplied into the interior of the pipe 12. Preferably, the gas is supplied to the T-connection 28 by a suitably connected conduit 30 having a control valve 32 and a conventional zero regulator 34 therein, such as is schematically illustrated in Figure 1.

Disposed within the hollow body or pipe 12 in surrounding relationship to the forward end of the tube 16 is a relatively short tubular element 36 having the outer periphery of its rear end suitably secured to the interior periphery of the pipe. The forward end of the tubular element 36 is provided with fan blades 38 preferably constructed in a manner similar to the blades 26. However, as shown in Figure 2, four such blades are struck from the end of the element and each is bent inwardly at a longitudinal edge so as to impart a clockwise rotation to the gaseous materials passing therethrough.

In the operation of the device, air is supplied at any desired pressure through tube 16. As the air issues from the end of the tube the fan blades 26 direct the air outwardly toward the interior periphery of the pipe 12 and impart a rotary motion to the air. This rotary motion produces a high pressure on the periphery of the blades and a relative negative pressure at the center of the blades. In addition, a slight venturi effect is caused by the constriction of the tube 16 where the tube end is bent to form the fan blades. This venturi effect aids in the production of the negative pressure. The negative pressure thus created in the area within the body surrounding tube 16 rearwardly of the forward end thereof, acts to inspirate the gas and the rotary motion of the air starts mixing the air with the gas.

The supply of gas is controlled by the zero regulator 34 and valve 32 acting in series. The correct amount of gas is first set by the valve 32 and then any change in the air setting, by air valve 24, will automatically inspirate the correct amount of gas. While this arrangement is greatly preferred, it is possible to provide only a valve in the gas conduit and to control both air and gas manually.

The gas from conduit 30 enters the pipe 12 through T-connection 28 and the fact that the gas is able to enter at the negative or low pressure center of the fan allows the gas and air to join before the fan blades 26 are reached. The gas and air are then rotated together, causing good mixing to occur before the second fan blades

38 are reached. The blades 38 then direct the rotating mixture in an opposite direction so as to impart an opposite rotary motion thereto to complete the job of intimately intermixing the gas and air.

It can thus be seen that there has been provided a gas-air mixing device which employs the principle of the fan to create a negative pressure to cause inspiration of the gas and turbulence to cause mixing of the air and gas. Thus, the device of the present invention utilizes the negative pressure created to do the work of inspiriting the gas. When a gas zero regulator is employed, the device is capable of automatically proportioning the correct amount of gas for any amount of air fed. Moreover, it will be noted that the construction of the device is of such simplicity that it readily lends itself to economical manufacturing techniques. No moving parts are required and the relatively few number of parts employed may be easily fabricated by conventional methods.

The mixer of the present invention has been tested on many of the natural gas burners that are recommended for use with pre-mixers only, and the results have been successful in every instance. In some instances, better results were obtained. The mixer is operable under many conditions and mixes equally as well with low pressure air as high pressure air. Any type of control may be used to regulate both air and gas, and this flexibility makes the mixer applicable to systems where specialized equipment is normally required. For example, the mixer serves very well as a superheat burner.

It will be understood that the form of the invention shown and described herein is to be taken as the preferred embodiment of the same and that various changes may be made within the spirit of the invention and the scope of the appended claim.

I claim:

A device for mixing two gaseous materials comprising a hollow body, a tube having an end disposed within said hollow body for supplying one of said gaseous materials into the interior thereof, said tube end having fan blades struck therefrom for directing the flow of the one gaseous material issuing therefrom outwardly toward the interior periphery of said hollow body in a rotary motion so as to cause a negative pressure to exist in the hollow body rearwardly of said tube end, a conduit communicating with the interior of said hollow body rearwardly of said tube end for supplying the other of said gaseous materials therein so that the same will be drawn into the area of negative pressure and join with said one gaseous material and the rotary motion of the latter will act to mix the two, and a tubular element mounted adjacent the interior surface of said hollow body in substantially surrounding relation to said tube end, said tubular element having an end extending forwardly of said tube end, the forwardly extending end of said tubular element having fan blades struck therefrom for directing the mixed gaseous materials in a rotary motion in the opposite direction to intimately intermix the two.
